NO-SLIDE SCARF PIN-COMB SET

Susie M. Perkins, McPherson, Kans.

Application July 5, 1950, Serial No. 172,055

1 Claim. (Cl. 132—57)

1

This invention relates to scarf-fastening devices, and more particularly to a comb device arranged to hold a scarf in place over the wearer's hair.

A main object of the invention is to provide a novel and improved scarf-fastening device which is very simple in construction, which is easy to use, and which provides a very convenient and readily accessible means for securing a scarf to the wearer's hair.

A further object of the invention is to provide an improved scarf fastener of the comb type which is very inexpensive to manufacture, which is neat in appearance, which is sturdy in construction, and which provides a reliable means of fastening a scarf to the wearer's hair.

Further objects and advantages of the invention will become apparent from the following description and claims, and from the accompanying drawings, wherein:

Figure 1 is a pictorial view illustrating a scarf secured to a woman's hair by the use of an improved fastener constructed in accordance with the present invention;

Figure 2 is an enlarged front elevational view of the improved scarf fastener employed in Figure 1;

Figure 3 is an enlarged cross-sectional detail view taken on line 3—3 of Figure 2.

Referring to the drawings, and more particularly to Figures 2 and 3, the fastener is designated generally at 11, and comprises a comb 12, to the back of which is secured a flat, elongated strip of soft, penetrable material, shown at 13, said material being, for example, felt or the like. The strip 13 may be formed at one longitudinal edge thereof with a groove 14 which receives a rib 15 formed on the back of the comb and which may be secured to said rib by the use of suitable cement or the like. As shown in Figure 2, the strip 13 is coextensive in length with the comb 12 and, as shown in Figure 3, the strip 13 is substantially coplanar with said comb. Designated at 15' is a pin which may be inserted through the strip 13 in the manner shown in Figure 2, said pin being substantially longer than the strip 13.

In using the device, the comb is first inserted in the wearer's hair and the scarf, shown at 16 in Figure 1, is placed over the wearer's hair with the front edge of the scarf overlying the penetrable

strip 13 of the fastener 11. The front edge portion of the scarf 16 is then secured to the strip 13 by means of the pin 15' by inserting the pin through the scarf and the strip 13 in the manner shown in Figure 1. With the upper front edge portion of the scarf 16 secured as above described, the remaining portions of the scarf may be disposed in the usual manner around the wearer's head, and the ends of the scarf may be knotted, as shown in Figure 1 at 17, in the usual manner.

The fastener 11 may be made in any desired color to match the color of the wearer's hair or the wearer's costume, and the pin 15' may likewise be furnished in desired colors.

While a specific embodiment of an improved scarf fastener has been disclosed in the foregoing description, it will be understood that various modifications within the spirit of the invention may occur to those skilled in the art. Therefore, it is intended that no limitations be placed on the invention except as defined by the scope of the appended claim.

What is claimed is:

25 A scarf fastener comprising a comb having a back formed on its edge opposed to the teeth thereof with a centrally disposed longitudinally extending rib, and a relatively flat elongated body of soft penetrable material having its bottom edge formed with a channel for socketing the rib and having a convex top edge, said body being coextensive in length with the back of the comb and having opposing convex sides of substantially larger radius of curvature than said top edge, said sides protruding outwardly from the sides of the back of the comb.

SUSIE M. PERKINS.
